ARTICULATED COVER FOR JOURNAL BOXES

Ernest R. Viberg, Montreal, Quebec, Canada.

Application January 27, 1933, Serial No. 653,870

7 Claims. (Cl. 308—47)

This invention relates to hooded journal box covers of the articulated type in which the component elements are assembled in relatively movable relation to permit accurate fitting of the lid portion of the assembly to ensure complete closure of the journal box opening.

More particularly, the present invention resides in the provision of an improved articulated cover assembly in which the design of the component elements, comprising the lid proper, the lid closing spring, and the hood or spring housing, is improved so that the assembly of these elements in interlocking relatively movable relation and the application of such assembly to the journal box is greatly facilitated.

A particular feature of the present invention resides in providing the lid and hood elements of the cover assembly with complementary apertured portions through which extensions of the lid closing spring are passed to form part of the fastening means by which the lower portions of the lid and hood are secured together in relatively movable relation.

Another feature of the invention resides in the provision of novel fastening means between the hood and the upper portion of the lid which serves, in conjunction with the lid closing spring, to prevent complete separation of the component parts of the cover assembly during the relative movement which takes place between these parts when the lid is fitted to the journal box and during movement of the lid to open or closed position.

Other objects, characteristic features and advantages of this invention will be more readily understood from the following detailed description taken in connection with the accompanying drawings, in which

Fig. 1 is a front elevation of an articulated cover assembly provided in accordance with this invention.

Fig. 2 is a side elevation of the assembly appearing in Fig. 1, with the exception of the lid closing spring which is omitted for the sake of clearness.

Fig. 3 is a vertical sectional view through the cover assembly taken substantially along the line 3—3 of Fig. 1. A portion of the journal box is also shown in this view to illustrate the manner in which the cover assembly is applied thereto.

Fig. 4 is a front view of the lid portion of the cover assembly as it appears prior to the application of the lid closing spring and the hood or spring housing.

Fig. 5 is a fragmentary horizontal sectional view taken substantially along the line 5—5 of Fig. 4,

Fig. 6 is a front view of the hood or spring housing per se.

Fig. 7 is a fragmentary front elevation of a modified cover assembly provided in accordance with this invention.

Fig. 8 is a side elevation of the assembly appearing in Fig. 7. A portion of the journal box is also indicated by dotted lines in this view to indicate the manner in which the cover assembly is applied thereto.

Fig. 9 is a view similar to Fig. 8 but showing a further modification of the cover assembly.

Fig. 10 is a side elevation of the modified cover assembly appearing in Fig. 9.

Fig. 11 is a fragmentary horizontal sectional view taken substantially along the line 11—11 of Fig. 9.

Fig. 12 is a fragmentary detail view illustrating a slight modification of the construction appearing in Figs. 1 to 3 inclusive.

Fig. 13 is a fragmentary detail view illustrating a slight modification with respect to the pivotal connection between the lid and hood elements of the cover assembly.

The articulated cover assembly appearing in Figs. 1 to 6 inclusive comprises a lid 11, a lid closing spring 12, and a hood or spring housing 13.

A pair of hooks 14 are cast integral with the upper edge of the lid 11 and project beyond the outer surface of the lid as shown to advantage in Figs. 2 and 3. The central portion of the lid is provided with recesses 15 and with a pair of integral lugs 16 located adjacent the inner sides of the recesses. The front wall of the hood 13 presents parallel transversely curved portions 17 and 18 extending between the side walls 19, which carry the integral pintle receiving sleeves 20 and 21. At their lower ends the side walls 19 of the hood are shaped to provide substantially circular eyelet members 22 which are fitted in the recesses 15 of the lid and are provided with apertures 23 registering with similar apertures 24 formed in the lugs 16. Flanges 25 are cast integral with the side walls 19 of the hood to lie in a plane substantially parallel with the outer surface of the lid 11 and have their upper extremities shaped to provide rounded portions 26 loosely fitted beneath the hooks 14.

The lid closing spring 12 is a torsion spring presenting two coils 27 and 28 connected by an intermediate U-shaped portion 29 which constitutes an integral continuation of the inner terminal convolutions of the coil and carries a roller 30. The outer convolutions of the coils 27 and 28 are extended to provide a pair of parallel side

arms 31 having their lower ends bent outwardly at right angles to provide pin-like portions 32 which extend through the openings 24 of the lugs 16 and through the registering openings 23 formed in the eyelet members 22 of the hood. As shown to advantage in Fig. 3 the curved front wall portion 18 of the hood serves as a fulcrum in which the coils 27 and 28 of the lid closing spring are seated, the U-shaped portion 29 of the lid closing spring, together with the roller 30, being housed by the upper front wall portion 17 and the side walls 19 of the hood which also serve as a housing for the journal box lug.

15 The manner in which the articulated cover assembly is applied to the journal box is clearly shown in Fig. 3, in which 34 designates a journal box having the usual mouth opening 35 and pintle lug 36, the latter being provided with the 20 customary angularly related cam faces 37 and 38 adapted to co-operate with the roller 30 of the lid closing spring 12 to hold the lid in closed or open position. The pintle receiving sleeves 20 and 21 of the hood 13 are disposed at opposite 25 sides of the lug 36 and receive the ends of the pintle 39 which passes loosely through said lug. In the present instance the outer end of the pintle receiving sleeve 20 is shown partly closed by an annular flange 20' which provides an abutment for one end of the pintle 39, the other end of which is adapted to be engaged by one or more bent pintle retaining tongues 40 provided at the outer end of a pintle retaining liner 41 fitted in the pintle sleeve 21, said pintle retaining liner 30 being of the type described in my co-pending application Serial No. 651,749 filed Jan. 14, 1933. If desired, the pintle sleeve 20 may also be provided with a pintle retaining liner 41 similar to that shown in connection with the pintle sleeve 21, in which event the flange 20' at the outer end of the sleeve 20 will, of course, be omitted. The 40 advantage incident to providing pintle retaining liners 41 in both of the pintle sleeves of the hood resides in the fact that these liners take the wear 45 of the pintle and may be replaced at a relatively small cost when unfit for further service. When the lid is in the closed position shown in Fig. 3 the roller 30 bears on the cam face 37 of the lug 36 so that the spring 12 exerts pressure against the central portion of the lid 11 to hold the lid firmly against the contacting surfaces of the journal box surrounding the journal box opening 35. When the lid is raised to open position the roller 30 rides over the cam face 37 of the lug 36 and onto the cam face 38 so that the spring 50 then becomes effective to retain the lid in its open position.

60 The manner in which the lid 11 and the hood 13 are secured together in assembled relation permits these parts to have a certain freedom of relative sliding and angular movement which, as is well understood in the art, is frequently necessary in order to ensure proper fitting of the cover assembly to completely close the journal box opening in accordance with A.R.A. requirements relative to exclusion of dust, water, etc. In this connection it will be noted that a certain amount of clearance is reserved between the hooks 14 of the lid and the co-operating rounded 65 portions 26 of the hood. It will also be observed that a certain amount of clearance is reserved between the eyelet members 22 of the hood and the side walls of the lid recesses 15 in which these members are engaged. Due to this clearance and to the manner in which the eyelet members

22 of the hood are pivotally connected to the lugs 16 of the lid by the extensions 32 of the lid closing spring, it will be seen that the lid and hood are capable of what may be termed "universal movement" with respect to each other. Horizontal sliding movement of the lid and hood parallel with the front face of the journal box is permitted by reason of the sliding fit obtaining between the lid hooks 14 and the co-operating rounded members 26 of the hood and by reason of the fact that the eyelet members 22 of the hood are free to have a limited lateral movement in the recesses 15. Relative vertical movement of the lid and hood parallel with the front face of the journal box is provided for by the reservation of a certain amount of clearance between the rounded members 26 of the hood and the overlying portions of the lid hooks 14 and by making the extensions 32 of the spring 12 slightly smaller than the openings 23 and 24 through which they extend. The looseness of the upper connections between the hood and the lid as represented by the interengaging elements 14 and 26, as well as the looseness of the lower pivotal connections afforded by the extensions 32 of the lid closing spring, provide for a certain relative angular movement of the hood and lid in various directions.

10 In Figs. 7 and 8, I have shown a modified cover assembly in which each of the previously mentioned hooks 14 is replaced by a stud 43 cast integral with the outer face of the lid 11. This stud is passed through an opening formed in a lug 44 cast integral with the hood 13 and is made hollow at its outer end so that this end may then be riveted over or upset to form a head 45. The clearance reserved between the head 45 and the lid 11 is greater than the thickness of the lug 44 in order to provide for relative movement between the lid and hood. The opening in the lug 44 through which the stud 43 passes is also preferably made larger than the stud in order to provide for a certain relative movement of the lid and hood in a vertical direction.

115 The further modification shown in Figs. 7 and 8 resides in the provision of two lugs 16 lying at opposite sides of the recess 15 in which the eyelet 22 of the hood is fitted. These lugs 16 are connected together as at 16a to form a box-like housing for the eyelet 22 and are both provided with openings registering with the openings of the eyelet to receive the extensions 32 of the lid closing spring. The other parts appearing in Figs. 7 and 8 are the same as described in connection with the preceding figures.

120 In the further modification illustrated in Figs. 9 to 11, each side wall of the hood 13 is provided with an integral outwardly projecting lug 46 loosely fitted in a housing 47 cast integral with the outer face of the lid 11 so that these parts 46 and 47 perform substantially the same function as the parts 14 and 26 of Fig. 1 and the parts 43 and 44 of Figs. 7 and 8. As shown more particularly in Fig. 11, the lugs 46 are provided with inclined surfaces 46a which enable these lugs 46 to be sprung past the housing members 47 and into interlocking engagement therewith. In this connection it will be understood that there is sufficient spring in the side walls 19 of the hood to permit the lugs 46 to be sprung past the closed outer end walls 47a of the casing 47 when pressure is applied through the agency of a suitable press in which the lid and hood are placed for assembly purposes.

125 130 135 140 145 150 In each of the constructions described in the

foregoing, the side walls 19 of the hood 13 may be provided with registering openings 19a for the reception of a spring retaining pin such as that forming part of the subject matter disclosed in 5 my co-pending application Serial No. 642,065 filed Nov. 10, 1932.

In Fig. 12 there is shown a slight modification of the hooks 14 provided at the upper edge of the lid. In this case the hooks 14 are made 10 of greater length as compared with Figs. 1 and 2 so that the free ends of the hooks may be bent inwardly from the dotted line to the full line position shown in Fig. 12 to engage beneath the co-operating members 26 of the lid. The 15 advantage of this construction is that the portions of the members 14 extending beneath the co-operating members 26 will serve to hold the lid to the hood in case of failure of the pivotal connections afforded by the outwardly bent portions 20 32 of the spring arms 31.

In the modification shown in Fig. 13, the lower ends of the spring legs 31, instead of being bent outwardly to provide the portions 32 as previously described, are left straight and inserted 25 in suitable sockets 31a cast integral with the outer face of the lid. In this case the lugs 16 of the lid may be pivotally connected with the eye members 22 of the hood by suitable rivets 32a, one of which appears in Fig. 13. These 30 rivets 32a may, of course, be replaced by bolts or other suitable forms of pivotal connections that may be easily removed.

Having thus fully described what I now conceive to be the preferred embodiments of my invention, it will be understood that various other 35 modifications may be resorted to within the scope and spirit of the appended claims.

Having thus described my invention, what I claim is:—

40 1. An articulated cover assembly for journal boxes comprising a lid, a hood overlying the upper portion of the lid and provided with apertured portions registering with similar apertured portions of the lid located a substantial distance below the upper edge of the lid, a U-shaped spring mounted between the lid and hood with the arms of the spring extending downwardly along the outer face of the lid, the lower ends of said arms being bent outwardly to form pivots passing 45 through the said registering apertured portions of the lid and hood, said hood having a portion thereof projecting beyond the upper edge of the lid and provided with pintle receiving openings, and fastening means loosely connecting the hood 50 to the lid adjacent the said upper edge of the lid.

55 2. An articulated cover assembly for journal boxes comprising a lid, a hood pivotally secured to the lid, a substantial distance below the upper edge of the lid, lugs projecting horizontally from

the side walls of the hood adjacent the upper edge of the lid, and projections carried by the lid adjacent its upper edge, said projections being in the form of casings receiving said lugs therein, said hood having a portion thereof projecting beyond the upper edge of the lid and provided with pintle receiving openings. 30

3. An articulated cover assembly for journal boxes comprising a lid, a hood, loose pivotal connections between the lid and hood located a substantial distance below the upper edge of the lid, apertured lugs projecting outwardly from the sides of the hood adjacent the upper edge of the lid and studs carried by the lid and passing through said apertured lugs, the free ends of said studs being headed to retain the lugs thereon. 35

4. An articulated cover assembly for journal boxes comprising a lid, a hood, upper and lower fastening means loosely connecting said lid and hood, said upper fastening means comprising 90 studs projecting from the outer face of the lid adjacent its upper edge and passing through apertured portions of the hood lying parallel with the said outer face of the lid. 95

5. An articulated cover assembly for journal boxes comprising a lid, a hood overlying the upper portion of the lid and provided with apertured portions registering with similar apertured portions of the lid located a substantial distance below the upper edge of the lid, and a spring device mounted between the lid and hood presenting a pair of arms extending downwardly along the outer face of the lid, the lower ends of said arms being bent outwardly to form pivots passing through the said registering apertured portions of the lid and hood. 100 110

6. An articulated cover assembly for journal boxes comprising a lid, a hood overlying the upper portion of the lid and presenting side walls having their lower extremities pivotally connected to the central portion of the lid, members projecting outwardly from the upper portion of the lid and provided with sockets facing towards the side walls of the hood and lateral projections from the side walls of the hood received in 115 said sockets, said last mentioned projections being provided with bevelled surfaces to facilitate springing of said projections into said sockets. 120

7. An articulated cover assembly for journal boxes comprising a lid, a hood overlying the upper portion of the lid and provided with side walls having portions thereof offset outwardly to form lateral projections, socket members formed integral with the upper portion of the lid and receiving said projections therein, and means pivotal 125 130 connecting the lower side wall portions of the hood to the central portion of the lid.

ERNEST R. VIBERG.
